UNITED STATES PATENT OFFICE.

WALTER N. McCLELLAN, OF BROOKLYN, NEW YORK.

AUTOMATIC RAILWAY-CAR DOOR.

1,333,430.

Specification of Letters Patent.

Patented Mar. 9, 1920.

Application filed July 12, 1919. Serial No. 310,292.

To all whom it may concern:

Be it known that I, WALTER N. McCLELLAN, a citizen of the United States, and a resident of the city of New York, borough 5 of Brooklyn, in the county of Kings and State of New York, have invented a new and Improved Automatic Railway-Car Door, of which the following is a full, clear, and exact description.

10 This invention relates to railway construction and has particular reference to the automatic operation of side doors for railway cars such as are commonly used on subways and elevated lines as well as surface 15 cars operating along platforms on or about the same level as the car floors.

Among the objects of the invention is to provide means acting automatically between the station platform or the mechanism 20 beneath the platform and the car mechanism to cause the doors to open automatically coincidentally with the stopping of the car at the station.

Another object of the invention is to provide means under the control of the station agent or guard to prevent the motorman from shutting the doors and starting the car prematurely.

A still further object of the invention is 30 to provide a novel safety guard co-operating with the doors to bridge over the gap between the car platform and the station platform and acting also to prevent any passenger or patron of the road either on or 35 off of the car from occupying a position in which he might be injured as a result of the movement of any of the automatic devices.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section 50 of a car showing end and intermediate doors on the distant side of the car, the direction of movement of the car being understood to be toward the left.

Fig. 2 is an enlarged vertical longitudinal section of the front of the car, the section being on the line 2—2 of Fig. 3.

Fig. 3 is a vertical transverse section on the line 3—3 of Fig. 2 looking rearward.

Fig. 4 is a view similar to Fig. 2, but showing the front door held open, the view 60 being on the line 4—4 of Fig. 5.

Fig. 5 is a vertical transverse section on the line 5—5 of Fig. 4.

Fig. 6 is a plan view of one of the safety fenders arranged preferably on both plat- 65 forms on opposite sides of the door.

Fig. 7 is a diagrammatic plan view of a door showing guard rails carried thereby; and

Fig. 8 is a side elevation of a portion of 70 the station mechanism for controlling the closing of the doors of a number of cars.

Referring now more specifically to the drawings I show at 10 a railway track along which are arranged any suitable number of 75 ramps 11, each having a gradual rise terminating in a level or horizontal portion 11' for co-operation with a roller 12 constituting a shoe connected through a cushion 13 with a vertically movable plunger 14 carried by 80 guides 15 beneath the front end of the car. Said guides are shown in Fig. 3 as carried by a depending bracket 16 of any suitable rigid construction.

Within this bracket and preferably be- 85 tween the guides 15 is journaled on a horizontal axis 17 an arm 18 of bell crank construction the opposite arm 19 of which is connected by a link 20 to the lower end of a door actuating lever 21 pivoted at 22 on one 90 of the floor sills of the car. The floor 23 of the car or the car platform will be understood as being on the same level as the station platform 24, or approximately so. The upper end of the lever 21 has pin and slot 95 connection at 25 with the rear edge of the door 26 whereby when the lever is swung around its pivot 22 the door will be opened or subsequently closed. The middle door 26^a is actuated by the same kind of mecha- 100 nism including a lever 21 and operated from the first lever by means of a rod connection 27. The rear door 26^b being slideable in the opposite direction has its lever 21' reversed and the same is actuated by means of a 105 rocker 28 journaled at 29 and having rod connections 30 to the levers 21 and 21'. From this construction it follows that the doors are all opened simultaneously and positively by the lift of the roller 12 and plunger 14 when a ramp 11 is reached. The high end of the ramp registers with a mov-

able ramp member 11^a normally on the same level, but which by virtue of a bell crank 31 pivoted at 32 is adapted to be lowered, by any authorized person at the station platform by the manipulation of the lever 33 connected to one or more rods or links 34. This movable ramp 11^a will be of any suitable length to insure that the motorman will stop his car with the roller 12 resting thereon.

Pivoted beneath the door at 35 is a catch 36 the point of which is depressed by the door as it moves open, said point being adapted to enter a notch 37 near the front lower corner of the door and when the door is open (see Fig. 4) any suitable means may be provided to actuate the catch. To this end I show a flexible connection 38 with the end of the catch member remote from the point, said flexible connection leading over or around any suitable direction pulleys 39 mounted on a bracket 40 extending downward beneath the car platform. The bolt 41 is slidable through a guide 42 attached to the opposite end of the connection 38 and tends to be lifted by a spring 43 located between the guide 42 and a collar 44 near the upper end of the bolt. Among the functions of this spring, therefore, is to tend to hold the point of the catch elevated in position to enter the notch 37 and so hold the door open. If desired a safety spring attachment 45 may be interposed at any desired point between the ends of the flexible connection 38.

After the movable ramp 11^a is depressed or withdrawn from the roller 12 to allow the doors to be closed, any suitable means under the control of the motorman may be employed to close the doors preferably by motor means. To this end I provide for each door a compressed air motor 46 having a reciprocating piston 47 with a rod and link connection 48 with the lever 21. The door may be operated in either direction by means of compressed air admitted into the motor cylinder from a storage tank 49 located at any convenient point on the car, and which may be operated in the other direction by a spring 50. As shown herein the spring acts in conjunction with the ramp mechanism to open the door and for closing the door the motorman first opens a trip valve 51 to admit compressed air into the trip motor 52 through a branch pipe 53 which acts upward on the front end of the catch to withdraw the point of the catch from the notch 37. Immediately thereafter the motorman will open the valve 54 in the main air line 55 to admit the power fluid into the main cylinder 46. This description will of course apply to the motors on all the doors, they all being connected to the same air line 55. Carried by the car on opposite sides of the bottom of each door

and pivoted at 56 and 57 are inner and outer bridge members 58 and 59 respectively. The normal position of these bridge members when the car is running is as shown in Figs. 2 and 3 close to the door. A pair 70 of links 60 are pivotally connected to these bridge members above their axes and extend downward to a point of connection 61 with the upper end of the bolt 41. Coincidentally therefore with the swinging of 75 the catch 36 downward by direct contact therewith of the door the flexible connection 38 will draw downward upon the links 60 and throw the bridge members downward flush with the car and station platforms 80 thereby serving several important functions: First, to substantially bridge the gap between the two platforms, and secondly to depress the inner and outer fenders 62 and 63 movable upward across the surface of the 85 two platforms respectively. The upward movement of the fenders is effected by springs 64, the combined force of which and the spring 43 is not greater than that of the safety spring 45. When the door is shut 90 and the bridge members are in normal elevated position the fenders are lifted to the position shown in Fig. 3, and the position of the fenders is such as to prevent any occupant of either platform from standing so 95 that his foot may be in danger of being injured by the swinging bridge member. Should, however, a person or object be caught between the bridge and the fender serious damage will be prevented by the 100 spring 45. As shown in Fig. 6 the ends of each fender may be arranged at an angle or curved so as to more effectively guard the region of the bridges.

Each door is preferably provided with 105 inner and outer guard rails 65 bowed as indicated in Fig. 7 and serving to gently but positively force any person away from the door far enough so as not to be endangered either by the door or any of the parts movable adjacent thereto.

I claim:

1. The combination with a railway car and a plurality of sliding doors carried thereby, of means to automatically open all 115 of the doors simultaneously when the car reaches a predetermined point along the railway, said opening means comprising a ramp located along the track, a shoe carried by the car and movable by contact with the ramp in a direction transverse to the direction of movement of the car, lever and link connections between the shoe and all of the doors, and means to lock the doors open.

2. The combination with a railway car and a sliding door carried thereby, of means to automatically open the door when the car reaches a certain point along the track-way, means to lock the door open, and 130

means manually controlled from a distance to release the door locking means.

5 3. The combination with a railway car and a door carried thereby, means to automatically open the door, a member actuated by the door during its opening movement and serving to lock the door open, and bridge means adjacent to the door actuated by said door member to be moved into 10 bridging position simultaneously with the opening of the door.

15 4. The combination with a railway car, a door carried thereby and automatic means to open the door, of a member serving to lock the door open, said member being in the form of a lever pivoted beneath the door and moved on its pivot by contact therewith during the opening of the door, bridging means serving to close the gap between 20 the car platform and the station platform, and connections between said pivoted locking member and the bridge means whereby the bridge means is moved into bridging position automatically and simultaneously 25 with the opening of the door.

30 5. The combination with a railway car having a sliding door and a platform adjacent thereto and means to automatically open the door, of a member pivoted beneath the platform and actuated by the lower edge of the door while being opened, said lower edge of the door being provided with a notch into which said member engages to lock the door open, and means controllable from a distance from the door to release said member to permit the door to close.

35 6. The combination of a railway car hav-

ing a door and a platform adjacent thereto, means to automatically open the door, a lever pivoted beneath the platform and engageable by the door in open position to lock the door open, a bridge member carried by the platform and movable toward and from the door, and flexible and resilient 45 connections between said lever and the bridge member to cause the bridge member to be moved into horizontal position automatically during the opening of the door.

50 7. In car door mechanism, the combination with a sliding door, bridge members arranged normally in vertical position on opposite sides of the door, means to open the door and hold it open, and connections between the door holding means and the 55 bridge members to cause the bridge members to be swung downward in a horizontal position automatically and simultaneously with the opening of the door.

60 8. In car door mechanism, the combination of a door, means to slide it open and closed, and guard means adjacent to the door serving to gently but positively force passengers away from the door while it is moving.

65 9. In car door mechanism, the combination of a door, means to slide the door open and closed, movable bridge members adjacent to the door, means to spring the bridge members down into horizontal position while the door is being opened, and fender means to prevent injury to passengers either inside or outside of the door when said bridge members are being moved.

70 WALTER N. McCLELLAN.
